UNITED STATES PATENT OFFICE.

PAUL S. LUTTRELL, OF OAKLAND, AND PAUL C. ROSKE, OF SAN FRANCISCO, CALIFORNIA, ASSIGNORS TO AMERICAN CLOCK CORPORATION, OF OAKLAND, CALIFORNIA, A CORPORATION OF CALIFORNIA.

CLOCK STRUCTURE.

Application filed September 19, 1922. Serial No. 589,125.

To all whom it may concern:

Be it known that we, PAUL S. LUTTRELL and PAUL C. ROSKE, citizens of the United States, residing at Oakland, county of Alameda, and at the city and county of San Francisco and State of California, respectively, have invented new and useful Improvements in Clock Structures, of which the following is a specification.

10 This invention relates to a clock mechanism and especially to that type employed in the cheaper grades of clocks, such as kitchen clocks, alarm clocks, etc.

There are a number of clock structures, 15 both of the cheaper and better grades manufactured today, but the majority of them is so constructed and assembled that repair, in case of breakage, is out of the question, that is the average watchmaker, due to the in- 20 accessibility of the parts and the difficulty of assembling the same, charges more for repair work than the entire clock mechanism is worth. Practical experience shows that the average structure of this character must be completely taken apart even though the mechanism to be repaired or replaced only forms a minor part of the structure. Experience also shows that the 25 main spring and the alarm actuating spring, together with the surrounding barrels and winding mechanism associated therewith are the parts most frequently broken, and as these parts are usually difficult to remove and replace, repair thereof is seldom under- 30 taken.

Having a general knowledge of clock structures and being familiar with the defects and facts above stated, we have sought to generally improve and simplify clock 40 structures of the character described. First, by generally improving and simplifying the mechanism as a whole and the assembly thereof; secondly by so arranging the individual parts of the mechanism that 45 they may be readily removed or replaced for repair, etc. without difficulty or undue loss of time; and third by arranging and assembling certain groups of the mechanism that they may be removed and replaced 50 as individual units without disturbing the remaining mechanism.

Further objects will hereinafter appear. The invention consists of the parts and the construction, combination and arrangement of parts as hereinafter more fully described and claimed, having reference to the accompanying drawings, in which—

Fig. 1 is a side elevation of a standard form of clock mechanism, showing the application of our invention.

Fig. 2 is a cross section on line 2—2, Fig. 1.

Fig. 3 is a perspective view of one of the bearing plates.

Fig. 4 is a perspective view of one of the 65 spring barrels employed.

Referring to the drawings in detail, A indicates in general a standard form of clock mechanism and B the main frame supporting said mechanism. The main frame usually consists of a front and rear plate, such as indicated at 2 and 3. These plates are interspaced and are so maintained by stud bolts such as indicated at 4, 5, 6 and 7. These bolts are disposed at the respective 70 corners of the main frame and are secured in place by nuts 8 as indicated. The several parts of the clock mechanism employed, such as the main spring, the gear train actuated thereby, the balance wheel, the escapement, etc., are journaled between the plates 2 and 3 and as such cannot be removed except by releasing one of the frame plates, for instance that indicated at 2. The plate 2 is held in position, as previously 75 stated by means of the four nuts indicated at 8, and all of these must be released before the plate 2 can be removed. Removal of this plate releases the entire mechanism and considerable trouble and time is lost 80 in replacing the same when assembling the mechanism. It is the time element involved that usually makes repairwork of clocks of this character costly and it is for this reason that repairwork is seldom attempted. 85

As stated in the preamble of the specification the parts most subject to wear and breakage are those associated with the main spring and the alarm actuating spring. The springs are also subject to breakage and our object is to so support and mount these 100 groups of mechanism that they may be re-

moved as individual units without releasing or in any way disturbing the main frame plates 2 and 3, between which the major portion of the mechanism is disposed. This is accomplished as follows: By referring to Figs. 1, 2 and 3, it will be seen that a pair of supplemental bearing plates, such as indicated at C and D, has been provided. The plate C carries the main spring, together with associated winding and driving mechanism, while the plate D carries the alarm spring with associated winding and driving mechanism. The main frame plate 2 is cut away, as indicated by the dotted line 10 at 9, to receive the main spring 10, the barrel 11 enclosing the same, and the winding mechanism connected therewith, as generally indicated at 12. The main frame plate 2 is also cut away as indicated by dotted line 20 at 14, to receive the alarm spring together with the enclosing barrel and associated mechanism. The bearing plates indicated at C and D are identical in construction and the mechanism supported thereby is similarly so, and we will for this reason only explain the specific structure of the plate C.

By referring to Figs. 1 and 3, it will be seen that the exterior contour or general 30 shape of the plate C may be such as the particular clock mechanism or structure employed may demand, and may for this reason be varied. Formed on one end of this plate is a projecting lug 15, which is adapted to be received by a slot 16 formed in the main frame plate 2. Formed at the opposite end of the bearing plate is a slot 17, which permits straddling of the stud bolt 7, and adapted to engage this end of the bearing plate and secure it in a position 40 is a washer and a nut 8, as indicated. The bearing plate has journalled therein a ratchet gear 18, and it furthermore carries a pivotally mounted pawl 19 and a spring 45 20 whereby engagement is maintained between the pawl and gear 18. The ratchet gear 18 is, as previously stated, journalled in bearing plate C so it is free to rotate therein; the rotation being in one direction 50 as it is positively locked against reverse rotation by pawl 19. The ratchet gear is furthermore locked against endwise movement in the plate and as such forms a permanent attachment or part thereof. Such 55 endwise movement is prevented by an inner annular flange 21. Formed centrally of the ratchet gear is a square or, as here shown, hexagonal opening 22, and extending therethrough is a hub member of similar shape 60 as indicated at 23, see Figs. 2 and 4. The spring barrel 11 is riveted, flanged or otherwise secured to the inner end of the hub member so as to rotate in unison therewith when the main spring 10 is to be wound, and 65 it will to this extent form a permanent part

of the hub member 23. This hub member forms several functions, first that of rotating the barrel when the spring is to be wound; secondly that of retaining the barrel against reverse movement when the clock 70 is in operation; third that of a support for the barrel and spring contained therein; fourth that of a bearing member for the inner end of the spindle indicated at 24, and fifth it supports the winding key generally indicated at 25; the outer end of the hub being threaded to receive a threaded extension or shank on the key as indicated at 26.

The main spring 10 is secured at its outer end to the barrel in any suitable manner, but preferably as here shown by engagement with a hook portion 27, which is pressed out of the rim of the barrel as shown in Fig. 4. The inner end is secured to the driving spindle 24 in the usual manner by engaging it with the pin 28.

A spring unit constructed and supported, as here shown may obviously be removed in its entirety without releasing or in any way disturbing the main frame plates or the mechanism supported thereby as it is only necessary to release the nut 8 and to lift the bearing plates C upwardly to disengage the lug 15. This operation can be quickly and readily accomplished and the time element involved should therefore be of no consequence or expense, and another new unit may be placed in the same fraction of time and the total cost should in a case of this kind not amount to much more than the actual cost of the mechanism replaced. Repairing of alarm clocks and cheaper grades of mechanisms of this character can be cheaply and readily accomplished and excess charges for such work will be entirely avoided.

The alarm spring, together with the mechanism associated with and actuated thereby, is identical to that illustrated in connection with the main spring. It is furthermore removed and replaced in an identical manner and a detail description thereof is for this reason thought unnecessary.

From the foregoing description it should be obvious that one of the important features of the present invention is the provision of auxiliary bearing plates such as indicated at C and D, which may be quickly and readily removed without disturbing the remaining mechanism. Another important feature is that the main and alarm springs and associated mechanism are entirely carried and supported by these plates and may therefore be removed in unison with the same. Another important feature is the provision of a spring barrel, such as indicated at 11, which is adapted to receive and enclose the springs whether it be the main or alarm spring; these spring barrels being

permanently attached to hub members 23, which may be readily removed with relation to their respective ratchet gears and bearing plates, that is if one of the springs 5 should break, it would not be necessary to replace the whole assembly, consisting of the bearing plate, the ratchet gear, pawl, spring, hub, barrel and the spring mounted interior thereof, but it would only be necessary to 10 replace the hub 23, the barrel 11 and the spring contained thereby, or in other words the unit shown in Fig. 4; the unit indicated in Fig. 3 being retained as it is subject to so little wear and strain that breakage of 15 any of the parts employed is rather improbable and would at least seldom occur. A watchmaker in making such a repair would therefore only have to replace the barrel and spring and thereby further reduce the cost 20 of such repairs.

While certain features of the present invention are more or less specifically illustrated, we wish it understood that various changes in form and proportion may be 25 resorted to within the scope of the appended claims, similarly that the materials and finish of the several parts employed may be such as the experience and judgment of the manufacturer may dictate or various uses 30 may demand.

Having thus described our invention, what we claim and desire to secure by Letters Patent is—

1. In a clock mechanism of the character 35 described the combination with the main frame plate, of a bearing plate carried thereby, a main driving spring and associated winding mechanism attached to said bearing plate, a projection on one end of the bearing 40 plate, said main frame plate having means for receiving the projection on the bearing plate and to form an interlocking connection, and means for securing the other end of the bearing plate with relation to the 45 main frame plate.

2. In a clock mechanism of the character described the combination with the main frame plate and the bearing plate associated therewith, of a lug formed on one end of 50 said bearing plate and having a slot formed in its opposite end, said main plate also having a slot formed therein to receive said lug, a screw carried by the main plate adapted to be straddled by said slotted portion of 55 the bearing plate, and a nut on said screw to secure the slotted end of the bearing plate.

3. In a clock mechanism of the character 60 described, a main frame, a detachable bearing plate carried thereby, a ratchet wheel journaled in said bearing plate, a pawl and spring also carried by the plate and cooperating with the ratchet wheel to lock it against rotation in one direction, and means 65 securing the ratchet wheel against endwise movement with relation to the bearing plate.

4. In a clock mechanism of the character 70 described, a main frame, a detachable bearing plate carried thereby, a ratchet wheel journaled in said bearing plate, a pawl and spring also carried by the plate and cooperating with the ratchet wheel to lock it 75 against rotation in one direction, means securing the ratchet wheel against endwise movement with relation to the bearing plate, a hub member endwise movable in the ratchet gear, means securing said hub member 80 against turning movement with relation to the ratchet gear, a spring barrel secured to one end of the hub member and a spring within said barrel.

5. In a clock mechanism of the character 85 described, a main frame, a detachable bearing plate carried thereby, a ratchet wheel journaled in said bearing plate, a pawl and spring also carried by the plate and cooperating with the ratchet wheel to lock it 90 against rotation in one direction, means securing the ratchet wheel against endwise movement with relation to the bearing plate, a hub member endwise movable in the ratchet gear, means securing said hub member 95 against turning movement with relation to the ratchet gear, a spring barrel secured to one end of the hub member, a spring within said barrel, a spindle extending through the spring and the barrel, and having one end 100 journaled in the hub, means for securing one end of the spring to said spindle and the opposite end to the barrel, and a winding key detachably secured with relation to said hub member.

6. In a clock mechanism of the character 105 described the combination with the detachable bearing plate, of a ratchet gear journaled in said plate, said gear having a hexagonal shaped central opening formed therein, means securing said gear against endwise movement in the plate, a spring retaining barrel and a hub member forming a part 110 thereof, said hub member having a hexagonal exterior shape to permit endwise insertion in the ratchet gear and removal with relation thereto.

7. In a clock mechanism of the character 115 described a spring enclosing barrel, a hub member forming an integral part thereof, a spindle adapted to be driven by the spring in the barrel, said spindle being endwise removable with relation to the spring and the barrel, and a bearing member in one end of the hub to receive said spindle.

8. In a clock mechanism of the character 120 described, a spring enclosing barrel, a hub member forming an integral part thereof, a hexagonal surface formed on the exterior of the hub, a ratchet gear journaled in the 125 clock, and having a hexagonal shaped central opening formed therein to receive the hub, and to permit endwise removal of the hub and the barrel.

9. In a clock mechanism of the character described the combination with the main frame and the mechanism carried thereby, of an auxiliary bearing plate carried by the frame, said main frame being slotted to receive a lug formed on one end of the bearing plate, and to permit a hingelike

movement of the bearing plate with relation to the main frame to permit insertion or removal thereof, and means carried by the main frame for securing the opposite end of the bearing plate.
